ART OF CONVERTING OILS

Filed Dec. 19, 1921

Inventor:
Edgar M. Clark,
By appointment of
Chittenden, Vt., U.S.A.
Attys.

UNITED STATES PATENT OFFICE.

EDGAR M. CLARK, OF NEW YORK, N. Y., ASSIGNOR TO STANDARD DEVELOPMENT COMPANY, A CORPORATION OF DELAWARE.

ART OF CONVERTING OILS.

Application filed December 19, 1921. Serial No. 528,468.

To all whom it may concern:

Be it known that I, EDGAR M. CLARK, a citizen of the United States, residing at 1 W. 64th Street, New York city, in the county of New York and State of New York, have invented a new and useful Improvement in the Art of Converting Oils, of which the following is a specification.

The present invention relates to the art of converting oils and more particularly to the conversion of hydrocarbon oils into lower boiling-point hydrocarbon oils, such as gasoline, by the action of heat. It will be fully understood from the following description, illustrated by the accompanying drawing, in which apparatus suitable for carrying out the invention is diagrammatically shown, partly in section.

In carrying out my invention, any suitable hydrocarbon oil stock of higher boiling point than the desired products may be employed, for example, an overhead stock such as gas oil, having a boiling point range of 550 to 750° F. under atmospheric pressure, or residue oils, such as skimmed or topped crude oils from which the lower boiling point constituents, such as gasoline and kerosene, have been removed by distillation. For example, a light Mexican crude oil from which gasoline and kerosene have been removed, may be employed. Crude oils, such as heavy Mexican crude oil, which contain no substantial proportion of lower boiling point products, may likewise be treated in accordance with the present invention.

Referring to the drawings, the stock to be converted is fed by pump 1 through the highly heated coil 2, in which it is brought to an effective conversion temperature, for example, to a temperature above 680 to 700° F. A slight pressure is maintained upon the oil in the coil 2, this pressure being in general less than 40 to 50 lbs. per square inch and preferably about 25 lbs. per square inch. The pressure in coil 2 is not sufficient to maintain the unconverted oil entirely in the liquid phase, a substantial proportion thereof being vaporized in its travel through the coil. The rate of flow of the

oil through the coil is controlled so that there is no substantial deposition of coke therein, the rate of firing being adjusted with reference to the rate of flow of the oil so that the temperature of the oil products at the outlet of the coil is maintained at the desired point. The vaporization of portions of the oil in the coil aids in increasing the velocity of its flow therethrough. On leaving the coil the oil does not contain any high proportion of low boiling point products, only a small amount of cracking having been effected therein. In operating upon an oil of the character of gas oil for the production of gasoline, a pressure of 25 lbs. may be maintained in the coil 2 and the rate of firing of the coil so controlled that the temperature of the oil products at the outlet of the coil is about 800° F.

From the coil the oil products enter the intake side of a compression pump 3, by which the oil products are compressed and forced into a drum or chamber 4, through which they pass while undergoing continued conversion and digestion. The oil products leaving the coil 2 are compressed by the pump 3 to a pressure at which the unconverted oil is substantially entirely in liquid state. This pressure is, in general, in excess of 75 lbs. per square inch and may suitably be about 200 lbs. when the oil products leave the coil 2 at a temperature of about 800° F. The compression by the pump 3 being substantially adiabatic, a substantial increase in temperature of the oil products results, say 50 to 75° F. The products leaving the coil 2 at 25 lbs. pressure and 800° F. in the specific instance set forth in the preceding paragraph, on compression by the pump 3 to 200 lbs. pressure, acquire a temperature of about 850° F. at which they enter the chamber or drum 4.

The chamber 4 may suitably be heavily lagged with heat insulating material to reduce the loss of heat as far as possible. Means may be provided, if desired, for applying a relatively mild heat to this chamber or drum, for example, by conducting

the waste combustion gases from the setting of the coil 2 through a flue 5 into the setting of the drum 4. The heat applied to the drum 4 should at no time be sufficient to raise the wall of the drum to a temperature above 900° F. and ordinarily is not more than is required to maintain the temperature of the oil products within the drum. The proportions of the drum 4 are such that the heated oil products remain therein for a period sufficient to effect a substantial conversion of the oil into the desired low boiling point products, and may be, for example, one and one-half hours or more. In operating under the specific conditions above set forth, with the oil products entering the drum 4 from the compression pump at a pressure of about 200 lbs. and a temperature of about 850° F., the oil products may leave the drum at a temperature of from 800 to 850°. While it is desirable to maintain the temperature of the oil products within the drum 4 at about the temperature at which they enter the drum, a decrease in their temperature to not less than 680 to 700° F. may be permitted therein. A more or less copious deposition of coke, depending upon the nature of the oil treated, may take place in the drum, and is of such character as to be readily removable.

The oil products, after traveling through the drum 4, leave the drum through an outlet pipe 6, suitably provided with a pressure release valve 7. After the pressure upon the oil products has been released, they enter a separating chamber 8, preferably above a suitable transverse baffle plate or pan 9 provided therein. In this drum a separation of the products of conversion into liquid and vapors takes place, the liquids or tars being discharged through a pipe 10 and the vapors passing off through a vapor line 11 to a suitable condenser 12, from which the condensed and uncondensed products pass through a line 13 to a suitable receiver, not shown, in which they may be separated. It is generally desirable that a slight pressure, say 10 to 20 lbs., be maintained in the separating drum 8 to aid in the discharge of the oil products therefrom.

Although the present invention has been described in connection with specific details of procedure and apparatus for carrying it into effect, it is not intended that these shall be regarded as limitations upon the scope of the invention, except in so far as included in the accompanying claims.

I claim:

1. The method of converting hydrocarbon oils into lower boiling point hydrocarbon oils which comprises heating the oil to be converted to a temperature above 680 to 700° F. at a rate such that no substantial proportion of desired low boiling point

products is formed during said heating, compressing the heated oil material to a pressure at which the unconverted oil is substantially entirely in the liquid state and retaining the heated oil material under such pressure without reduction in temperature below 680 to 700° F. to effect substantial conversion thereof.

2. The method of converting hydrocarbon oils into lower boiling point hydrocarbon oils which comprises heating the oil to be converted to a temperature above 680 to 700° F. while under a pressure below that at which the substantially unconverted oil is substantially entirely in the liquid state at such temperature, compressing the heated oil material to a pressure at which the unconverted oil is substantially entirely in liquid state and maintaining the compressed oil material under such pressure and at a temperature above 680 to 700° F. to effect substantial conversion thereof.

3. The method of converting hydrocarbon oils into lower boiling point hydrocarbon oils which comprises rapidly heating the oil to be converted to a temperature of about 800° F., compressing the heated oil material to a pressure at which the unconverted oil is substantially entirely in liquid state and retaining the heated oil material under such pressure and at a temperature above 680 to 700° F. to effect substantial conversion thereof.

4. The method of converting hydrocarbon oils into lower boiling point hydrocarbon oils which comprises heating the oil to be converted to a temperature above 680 to 700° F. while passing through a confined passage, compressing the heated oil material issuing from said passage to a pressure at which the unconverted oil is substantially entirely in the liquid state, and passing the heated oil material under such pressure through an enlarged chamber while maintaining it at a temperature above 680 to 700° F. whereby a substantial conversion of the oil material is effected in said enlarged chamber.

5. The method of converting hydrocarbon oils into lower boiling point hydrocarbon oils which comprises heating an oil having an initial boiling point of about 550° F. to a temperature above 680 to 700° F. while passing through a confined passage, the oil being maintained in said passage at a pressure below 35 to 50 lbs. per square inch, compressing the heated oil material issuing from said passage to above 75 lbs. per square inch whereby oil of the character of substantially unconverted oil is brought to a liquid condition and retaining the heated oil material under such pressure at a temperature above 680 to 700° F. to effect substantial conversion thereof.

6. The method of converting hydrocarbon oils into lower boiling point hydrocarbon

oils which comprises passing the oil through converted oil is substantially entirely in the a highly heated confined passage at a rate liquid state and retaining the heated oil such that the oil acquires a temperature material under such pressure at a tempera-¹⁰ above 680 to 700° F. before substantial coke ture above 680 to 700° F. to effect sub-
5 deposition therefrom takes place, compress-
ing the heated oil material issuing from
said passage to a pressure at which the un-
